DOOR STOPRussell W. Ahlquist, New Britain, Conn., assignor to
The American Hardware Corporation, New Britain,
Conn., a corporation of ConnecticutFiled Feb. 2, 1959, Ser. No. 790,492
5 Claims. (Cl. 16—86)

This invention relates to a door stop and more particularly to a door stop of the type adapted to be mounted on a floor for engagement by the lower edge of a door to limit its opening movement.

The primary object of the present invention is to provide a door stop having novel means for fastening the resilient cushioning member thereof to the floor mounted base member.

A further object of the invention is to provide a door stop which is designed in such a way that it can be manufactured at considerably less cost than similar types of door stops presently available.

Further objects and advantages of this invention will be more clearly understood from the following description and the accompanying drawing in which:

FIG. 1 is an exploded, isometric view, illustrating the parts of a door stop embodying my invention.

FIG. 2 is a sectional, elevational view of the floor mounted base member of the door stop.

FIG. 3 is a bottom view of said base member.

FIG. 4 is a sectional, elevational view illustrating the resilient cushioning member of the door stop attached to the base member.

FIG. 5 is a bottom view of the assembled door stop illustrated in FIG. 4.

FIG. 6 is a sectional, elevational view illustrating a modified form of the door stop.

FIG. 7 is an isometric view of the retaining clip used in the modified door stop of FIG. 6.

The door stop illustrated in FIGS. 1 to 5 includes a base member 5 which is adapted to be mounted on a floor and is preferably formed in one piece by a suitable casting process. Said base member includes a circular plate portion 6 having an integral, hollow dome 7 formed at one side thereof. The dome has a spherical wall 8 forming one end of the base member 5 and an upstanding wall 9 which extends transversely across the plate portion 6 substantially diametrically thereof, said walls defining a cavity 10 which opens to the underside of the plate portion 6.

The upstanding wall 9 of the dome 7 has a notch 11 formed therein which extends upwardly above said plate portion 6 from the underside thereof as shown in FIG. 2. The plate portion 6 thus has a rear edge 6-a extending across said notch 11 which defines the lower side of a rectangular opening 12 in said wall 9 which communicates with the cavity 10.

The base member 5 is provided with a positioning stud 13 which is cast integrally with the spherical wall 8 of the dome 7 and projects downwardly from the cavity 10 below the underside of the plate portion 6. A countersunk hole 14 is formed in the plate portion 6 in axial alignment with said positioning stud 13 for the reception of a screw or other such fastening element for securing the base member to the floor.

It will be apparent to those skilled in the art, that the particular design of the base member 5 permits manufacture thereof by conventional cope-and-drag or shell molding processes without requiring the use of a core in the mold, thereby materially reducing the cost of producing the door stop. The exterior shape of the base member may be formed in one half of the mold, and the interior shape, including a projection for forming the notch 11, may be formed in the other half of the mold.

2

The fact that a core is not used and the "draw" is in the direction of the notch 11 permits formation of the countersunk hole 14 in the molding process, thereby eliminating subsequent machining operations and further reducing the cost of manufacture.

The base member 5 supports a resilient cushioning member 15 which is preferably made of rubber or like material and includes a head portion 16, which is substantially in the form of a right cylinder, and a rectangular shank portion 17 which extends rearwardly from the head portion 16 and is of a size and shape to closely fit the opening 12. The head 16 is larger than the shank, thus providing a flange 18 around the opposite sides and the top of said shank adapted to engage the outer surface of the wall 9 around the opening 12 therein as illustrated in FIG. 4. The flange is inclined rearwardly relatively to the vertical front surface of the head to conform to the inclination of the transverse wall 9 which is provided for convenience in casting. The shank portion 17 of the cushioning member is of a length to extend through the opening 12 and into the cavity 10 of the base member and is provided with a pair of spaced, vertical holes 19—19 therethrough adjacent the inner side of the wall 9.

The resilient cushioning member 15 is secured to the base member 5 by means of a retaining clip 20. Said clip is constructed from a single piece of wire and consists of a pair of spaced, parallel, L-shaped legs 21—21 having vertical portions 22—22 and horizontal portions 23—23 which are joined together by a bar portion 24. The vertical portions 22—22 extend through the holes 19—19 in the shank 17 and are of such length that the clip projects from the upper and lower sides of the shank. The upper free ends of the legs 21—21 engage the inner side of the wall 9 adjacent the edge of the opening 12, and the horizontally offset bar portion 24 of said clip is adapted to engage the edge 6-a of the plate portion 6 to thereby lock the resilient cushioning member to the base member as shown in FIGS. 4 and 5.

In order to assemble the door stop, it is only necessary to insert the shank 17 of the cushioning member into the opening 12 in the wall 9 of the base member and position the flange 18 on the cushioning member against said wall. The vertical portions 22—22 of the legs on the retaining clip 20 are then inserted into the holes 19—19 in said shank from the underside of the base member and said clip is positioned as illustrated in FIG. 4 to lock the cushioning member to the base member as above described.

The door stop is mounted on a floor by merely drilling a hole therein at the proper location to receive the positioning stud 13. Said stud is then inserted into the hole and after the stop is properly oriented, it is fastened in place with a screw which is driven through the countersunk hole 14 into the floor.

It will be noted from FIG. 4, that the lower horizontal end portion of the retaining clip 20 provides a foot which is disposed closely adjacent the underside of the base member so that said retaining clip is prevented from coming out of the holes in the shank through engagement of its said lower end with the floor upon which the door stop is mounted.

In FIG. 6 of the drawing, I have illustrated a modified form of door stop for use when a door has a threshold thereunder and its lower edge is consequently a greater distance from the floor than the lower edge of a door not having a threshold. Said door stop, indicated at 5-a, is essentially the same as the door stop 5 above described except that the plate portion 6-b thereof is provided with a depending annular skirt 25 which increases the height of the plate portion and therefore elevates the cushioning member 15 to a position wherein it will be engaged by the lower edge of the door.

The retaining clip 26 (see FIG. 7) used in the modified door stop 5-a is constructed from a single piece of wire formed to provide a U-shaped member having spaced parallel legs 27-27 which are interconnected at their lower ends by an integral bar portion 28. The lower vertical portions of said legs are forwardly offset from the upper vertical portions thus providing a knee 29 on each of said legs which is engageable with the edge 6-c of the plate portion of the door stop, as shown in FIG. 6, and cooperates with the upper free ends of said legs to lock the cushioning member 15 in position. The bar portion 28 is disposed substantially flush with the underside of the skirt 25 when the parts are assembled and thus forms a foot which is engageable with the floor upon which the door stop is mounted so that the retaining clip cannot become detached from the cushioning member.

I claim:

1. A door stop comprising a one-piece base member including a plate portion adapted to be mounted on a floor and an integral hollow dome extending upwardly from said plate portion and including an upstanding wall extending transversely across said plate portion, said dome forming a cavity having a mouth defined by the lower marginal edge portions of said dome and said wall and opening to the underside of said plate portion, said upstanding wall having a notch extending upwardly therein from the underside of said plate portion which forms an extension of said cavity and said mouth and terminates in an abutment, said notch being at least as wide at its lower end as it is at its upper end, and providing an opening in said wall communicating with said cavity, a resilient cushioning member mounted on said base member, said cushioning member having a head portion disposed against said wall in engagement with the outer face of its marginal edge portions adjacent said opening and a shank extending from said head portion through said opening and into said cavity, and a retaining member extending through the portion of said shank in said cavity and engaging said abutment and an inner face of said marginal edge portions adjacent the opening in said wall, whereby to lock said cushioning member to said base member.

2. The subject matter set forth in claim 1 wherein said retaining member comprises an L-shaped retaining clip having vertical portions extending upwardly through said shank and engaging said inner face of said marginal edge portions adjacent the opening in said wall, and a horizontal lower portion connecting said vertical portions and engaging said abutment.

3. The subject matter set forth in claim 1 wherein the portion of said shank within said cavity is provided with spaced parallel holes extending upwardly therethrough and said retaining member is of a U-shape having spaced parallel legs extending through said holes and projecting from the opposite sides of said shank into engagement with said abutment and said inner face of said marginal edge portions adjacent the opening in said wall.

4. A door stop comprising a base member including a plate portion adapted to be mounted on a floor, said plate portion having an annular depending skirt and an integral hollow dome extending upwardly therefrom and defining a cavity opening to the underside of said plate portion, said dome having an upstanding wall extending transversely across said plate portion and containing an opening therethrough communicating with said cavity, a resilient cushioning member mounted on said base member, said cushioning member having a head disposed against the outer side of said wall in engagement with the outer face of its marginal edge portions adjacent said opening and a shank extending from said head portion through said opening and into said cavity, the portion of said shank within said cavity having openings extending upwardly therethrough, a retaining member extending upwardly through said openings and having portions projecting from the opposite sides of said shank into engagement with the adjacent inner face of said marginal edge portions whereby to lock said cushioning member to said base member, said retaining member having a depending portion terminating adjacent the underside of said skirt and engageable with the floor upon which the door stop is mounted to prevent disengagement of said retaining member from said shank.

5. A door stop comprising a one-piece base member including a plate portion adapted to be mounted on a floor and an integral hollow dome extending upwardly from said plate portion and including an upstanding wall extending transversely across said plate portion, said dome forming a cavity having a mouth defined by the lower marginal edge portions of said dome and said wall and providing an open bottom thereon, said upstanding wall having a notch extending upwardly therein from the underside of said plate portion which forms an extension of said cavity and said mouth and terminates in the plane of the outer face of the upstanding wall, said notch being at least as wide at its lower end as it is at its upper end and providing an opening in said wall communicating with said cavity, said hollow dome having a positioning stud therein depending from said dome and extending below said open bottom, the top and side of said stud being integrally formed with the wall of said dome, a resilient cushioning member on said base member, said cushioning member having a head portion disposed against said upstanding wall in engagement with the outer face of its marginal edge portions adjacent said opening and a shank extending from said head portion through said opening and into said cavity on opposite sides of said positioning stud, and means engaging said shank for fastening said resilient cushioning member to said base member.
